UNITED STATES PATENT OFFICE.

JOHN P. MIDDLETON AND HAROLD D. ROSS, OF PITTSFIELD, MASSACHUSETTS.

CUFF-BUTTON.

1,168,095.

Specification of Letters Patent.

Patented Jan. 11, 1916.

Application filed April 22, 1915. Serial No. 23,250.

To all whom it may concern:

Be it known that we, JOHN P. MIDDLETON and HAROLD D. Ross, citizens of the United States, residing at Pittsfield, in the county 5 of Berkshire and State of Massachusetts, have invented certain new and useful Improvements in Cuff-Buttons; and we do declare the following to be a full, clear, and exact description of the invention, such as 10 will enable others skilled in the art to which it appertains to make and use the same.

This invention relates to improvements in cuff buttons and more particularly to cuff buttons for what are termed "French cuffs." 15 The object of the invention is to provide a cuff button of this character so constructed that it may be used equally well with soft cuffs of thin material as with similar cuffs of thick material without sliding, twisting 20 or rotating.

With this and other objects in view, the invention consists of certain novel features of construction, and the combination and arrangement of parts as will be more fully 25 described and claimed.

In the accompanying drawings: Figure 1 represents a front elevation of a cuff with this improved button applied; Fig. 2 is a longitudinal section through the cuff showing 30 the button in side elevation; Fig. 3 is a central vertical section taken on the line 3—3 of Fig. 2; Fig. 4 is a transverse section taken on the line 4—4 of Fig. 2.

In the embodiment illustrated, a cuff button 1 is shown especially designed for use with French cuffs which are, as is well known, of the character composed of two thicknesses of material produced by turning over one end of the cuff as is shown 40 clearly in Fig. 1. This button 1 is molded or otherwise formed of a single piece of material and comprises a straight shank 2 of oblong shape in cross section and of uniform size throughout its length. Formed at one 45 end of the shank 2 and arranged centrally therewith is an elongated head 3 which may be ornamented or not as desired, and formed at the other end of the shank and arranged centrally with respect to the latter, is an 50 elongated base 4, the longitudinal axes of the head 3 and the base 4 lying in a plane disposed at right angles to the wide sides

of the shank 2. Disposed midway of the head 3 and base 4 and arranged centrally on the shank 2 is a circular disk 5, the faces of 55 which are milled or roughened as at 6. When the button is applied to use with a French cuff, the head 3 is passed through the alined button holes in the two folds of material at one end of the cuff, and the base 60 4 is passed through the alined button holes in the two folds at the other end, the disk 5 being designed to separate the two ends. The button is then turned until the elongated head and base extend transversely 65 across the button holes. This will bring the wide sides of the shank into contact with the edges of the button holes. When so disposed, the button is reliably held in the button holes of the cuff without any possibility 70 of its sliding or twisting, and hence it may be employed equally well with cuffs constructed of thin material such as silk as with cuffs composed of thicker material. The disk increases the bearing surface on 75 the cloth and hence prevents possibility of the sliding of the button and its consequent detachment. The milled sides of the disk and wide sides of the shaft hold the button in operative position, preventing its lateral 80 movement on the cloth.

We claim as our invention:

A cuff button made from a single piece of material comprising a straight shank oblong in cross section and uniform in size throughout its length, an elongated head centrally arranged at one end of said shank, an elongated base centrally arranged at the other end of said shank, the longitudinal axes of said head and said base lying in a 85 plane disposed at right angles to the wide sides of said shank, and a circular disk centrally arranged on said shank and disposed midway of said head and said base, substantially as and for the purpose set forth. 90 95

In testimony whereof we have hereunto set our hands in presence of two subscribing witnesses.

JOHN P. MIDDLETON.
HAROLD D. ROSS.
